US00D897339S

(12) **United States Design Patent** (10) **Patent No.:** **US D897,339 S**
(45) **Date of Patent:** **** Sep. 29, 2020**

(54) **MONITOR**

(71) Applicant: **LG DISPLAY CO., LTD.**, Seoul (KR)

(72) Inventor: **A-reum Lee**, Paju-si (KR)

(73) Assignee: **LG DISPLAY CO., LTD.**, Seoul (KR)

(**) Term: **15 Years**

(21) Appl. No.: **29/646,454**

(22) Filed: **May 4, 2018**

(30) **Foreign Application Priority Data**

Nov. 6, 2017 (KR) 30-2017-0051646

(51) **LOC (12) Cl.** **14-02**

(52) **U.S. Cl.**

USPC **D14/374**

(58) **Field of Classification Search**

(57) **CLAIM**

The ornamental design for a monitor, as shown and described.

DESCRIPTION

FIG. 1 is a front, right, top perspective view of the monitor showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof; and,

FIG. 8 is an enlarged top, front, left perspective detail view of the upper left portion of the monitor, showing the camera module.

The broken lines, shown in FIGS. 1-7, are for the purpose of illustrating portions of the monitor and form no part of the claimed design.

1 Claim, 8 Drawing Sheets
